CORD CLAMP

Karl E. Rogers, Niagara Falls, N. Y.

Application September 30, 1943, Serial No. 504,347

2 Claims. (Cl. 24—133)

This invention relates to new and useful improvements in cord clamps such as clothesline fasteners. One object of the invention is to provide a cord clamp which is simple in construction, economical to make, and easy to operate. Another object of my invention is to provide a cord clamp which minimizes wear on the cord and yet has a positive and self-locking action. These and other objects will more fully appear and the nature of the invention will be more fully understood as the description proceeds.

Prior art cord fasteners, as for example clothesline fasteners, have been made which clamp the cord between a stationary surface and a pivoted eccentric member over which the cord passes. Such devices are hard to operate, since when once clamped firmly on the cord the eccentric member is difficult to loosen. Prior fasteners of this type have relied upon serrations upon either the stationary surface, the eccentric pivoted member, or both, to grip the cord firmly and obviate its slipping. Such serrated surfaces, however, have a cutting effect upon the fibers making up the cord, and soon weaken or wear the cord completely out at the location where it is customarily clamped. My invention overcomes such disadvantages of previously constructed cord clamps. In the clamp of my invention the cord is held in clamped position by pressure between smooth curved surfaces of a substantial radius of curvature relative to the diameter of the cord, the clamping effect being obtained to a large extent as a result of the snubbing of the cord around a projecting curved surface. As a result, wear on the cord is reduced to a minimum, since it is subjected to neither sharp bends nor the cutting action of sharp surfaces. Furthermore, my clamp, although self-locking as a result of tension on the cord, may be readily released or tightened still further, both operations being carried out with one hand.

The invention will be more readily understood by reference to the accompanying drawing, in which

Figure 1 is a perspective view of a clothesline clamp made in accordance with my invention, and

Figure 2 is a cross-sectional view of the clamp shown in Figure 1, the section being taken along the line 2—2 in Figure 1.

Referring to the drawing in detail, my invention is embodied in a clothesline clamp including a base or standard indicated generally by the reference character 1. In Fig. 1 the base 1 is shown attached in operative position on a vertical surface 2 such as a house or post. The base con-

sists of a plate-like portion 3 which abuts and is held upon the support 2 by means such as screws 3', and two projecting flanges 4 and 5 extending longitudinally of portion 3, flange 4 being on one side of part 3 and part 5 on the other, the flanges being parallel and spaced so as to provide a substantial space therebetween. In the drawing, parts 4 and 5 are shown as being made separately from part 3 and as being joined thereto by means of screws 6. It is obvious, however, that parts 4 and 5 may be made integral with part 3. The clamp shown in the drawing has its parts made entirely of wood. It is within the scope of my invention, however, to make any or all parts of the device of suitable metals, plastics, or other materials having the necessary strength, weather resistance, and, in the case of those portions clamping the cord, an adequate coefficient of friction.

Flanges 4 and 5 are provided, as shown, with aligned holes for the reception of pivot pin 7, which has an enlarged head 8. For ease of assembly the pin is made of relatively large diameter and is provided with a short tapered point 15 on its forward end. The hole in flange 5 is denoted by reference character 9. Pivottally mounted on pin 7 between flanges 4 and 5 is a clamping member 10 having an upper cord receiving arm portion 11 and a lower clamp releasing arm portion 12. The rear surface 17 of pivoted member 10 is provided with a groove 13 which is preferably although not necessarily of a generally V shape with curved side walls as shown. The rear surface of the upper cord receiving arm 11 of member 10 may be curved as shown to allow the change of direction of the clothesline from a horizontal to a vertical direction to take place gradually. At the same time the appreciable length of the groove in the rear portion of arm 11 provides a substantial frictional retarding effect upon the cord 14 in addition to that produced by the cooperating cord gripping members 15 and 16 now to be described.

Such cooperating cord gripping members are composed of a smoothly rounded projection 15 on part 3 in the lower portion between flanges 4 and 5, and a substantially correspondingly shaped recess 16 in member 10 so positioned that the confronting surfaces of projection 15 and recess 50 16 remain approximately parallel throughout the small range of pivotal movement of part 10 in which clamping of the cord takes place. As shown in Fig. 2, groove 13 is discontinued at the location of recess 16.

55 The free end of cord 14 may be easily put

through the cord clamp by withdrawing pin 7, removing member 10, placing the cord in the groove in the arm, and then replacing member 10 and pin 7 in operative position. Alternatively, the free end of the cord may be threaded through the device in assembled condition by feeding such end down into groove 13 past projection 15, which is easily accomplished when the bottom arm of member 10 is swung to the right.

The clamping device shown in the drawings functions in the following manner. The free end of the cord is grasped and pulled until the cord is at the desired degree of tautness. Upon release of such lower free end of the cord, the tensioned horizontal portion of the cord exerts, by reason of its friction in the groove of the upper portion 11, a considerable clockwise turning moment upon member 10, since the upper portion 11 thereof acts as a lever. Clockwise turning of member 10 forces cord 14 to engage projection 15 and to be bent therearound and into recess 16. The snubbing of the cord resulting from its being bent around the projection, plus the clamping action on the cord resulting from its being pressed between the projection 15 and recess 16, provides sufficient gripping action upon the cord to hold it from slipping. Such holding of the cord is augmented by the friction on the cord exerted by the V shaped groove 13 on the curved rear side of upper arm 11. Additional tension upon the horizontal portion of cord 14 causes parts 15 and 16 to engage the cord still more firmly and to increase the holding effect contributed by the V shaped groove in arm 11.

When it is desired to tighten the cord to compensate for stretching thereof, such operation may be accomplished with one hand merely by grasping the cord below the bottom of portion 14 of member 10 and pulling it downward. This releases the clamp, allowing the cord to be additionally tightened. Release of the pull on the vertical portion of the cord results in the clamp automatically grasping and holding the cord at its new position.

Release of the clamp is effected merely by pulling the bottom part 12 of member 10 to the right. This separates recess 16 from projection 15, allowing withdrawal of the cord from the clamp. Because of the length of portion 12 relative to the effective length of portion 11, measured from pivot pin 7, such loosening operation is easily accomplished.

It is to be understood that the details of structure and arrangement of parts may be variously changed and modified without departing from the spirit and scope of my invention. For example, the projecting portion 15 of the clamp may be located on the portion 10 and the recess 16 may be located on the stationary portion 3 rather than as shown.

Having thus fully described my invention, I desire to claim as new the following:

1. A self-locking cord clamp comprising two relatively pivoted members, one of such members comprising a base having spaced vertically extending flanges projecting from one surface thereof, the other of the members comprising a clamping member located between the two flanges

and mounted thereon for pivotal movement in a vertical plane parallel to the flanges, the clamping member being provided with arms above and below the pivotal axis, the lower arm being appreciably longer than the upper arm, the surfaces of both the upper and lower arms confronting the base being provided with a V-shaped groove extending longitudinally thereof to receive a cord, means for gripping the cord between the clamping member and the base, said gripping means comprising a smoothly rounded smooth surfaced projection located on one of the two relatively pivoted members a short distance below the pivotal axis of the two members compared to the length of the upper arm of the clamping member, and an approximately correspondingly shaped recess located on the other movable member in confronting relation to the projection, the lower arm of the clamping member below the cooperating cord gripping means being of a length appreciably longer than that of the upper arm and extending substantially vertically below the pivotal axis, the grooved surface of the lower arm extending substantially vertically below the cord gripping means, whereby the end of the cord below the gripping means substantially contacts the groove on the lower arm throughout its length.

2. A self-locking cord clamp comprising two relatively pivoted members, one of such members comprising a base having spaced vertically extending flanges projecting from one surface thereof, the other of the members comprising a clamping member located between the two flanges and mounted thereon for pivotal movement in a vertical plane parallel to the flanges, the clamping member being provided with arms above and below the pivotal axis, the lower arm being appreciably longer than the upper arm, the surface of the upper arm confronting the pivot pin from an approximately vertical direction in the vicinity of the pivot pin to approximately a horizontal direction at the top of said upper arm, the surface of both the upper and lower arms confronting the base being provided with a V-shaped groove extending longitudinally thereof to receive a cord, means for gripping the cord between the clamping member and the base, said gripping means comprising a smoothly rounded smooth surfaced projection located on the base a short distance below the pivotal axis of the two members compared to the length of the upper arm of the clamping member, and an approximately correspondingly shaped recess located on the clamping member in confronting relation to the projection, the lower arm of the clamping member below the cooperating cord gripping means being of a length appreciably longer than that of the upper arm and extending substantially vertically below the pivotal axis, the grooved surface of the lower arm extending substantially vertically below the cord gripping means, whereby the end of the cord below the gripping means substantially contacts the groove on the lower arm throughout its length.

KARL E. ROGERS.
